UNITED STATES PATENT OFFICE

134,827

DESIGN FOR A VACUUM CLEANER ATTACHMENT KIT

George R. Coss, Detroit, Mich., assignor to Eureka
Vacuum Cleaner Company, Detroit, Mich., a
corporation of Michigan

Application November 1, 1941, Serial No. 103,999

Term of patent 14 years

To all whom it may concern:

Be it known that George R. Coss, a citizen of the United States of America, residing at Detroit, in the county of Wayne and State of Michigan, has invented a new, original, and ornamental Design for a Vacuum Cleaner Attachment Kit, of which the following is a specification, reference being had to the accompanying drawing, forming a part thereof, wherein:

The single figure is a perspective view of a vacuum cleaner attachment flit, showing my design.

The dominant feature of the design resides in the portion shown in full lines in the drawing.

I claim:

The ornamental design for a vacuum cleaner attachment kit, substantially as shown and described.

GEORGE R. COSS.
